CONE BARLOW AND EDWARD RICHARD CLAPP, OF DONNACONA, QUEBEC, CANADA.

FIBER-LAYING ROLL.

Application filed April 28, 1925. Serial No. 26,539.

This invention relates to improvements in fiber laying rolls for paper making machines and the objects of the invention are to provide positive counterbalancing mechanism 5 for relieving any required amount of the total weight of the fiber laying roll from the paper web as it passes between such roll and the suction couch roll whereby the deflection of the fiber laying roll, without regard for 10 the effect of its weight on the paper web or the Fourdrinier wire, is prevented.

Further objects are to regulate the pressure of the fiber laying roll on the paper web to any required degree, thereby assuring a 15 uniform finish on both sides of the finished sheet of paper under all conditions and to relieve the wear and tear on the Fourdrinier wire caused by the too excessive weight of the fiber laying roll running thereon.

20 A still further object is to provide counterbalancing mechanism for rapidly and effectively varying the setting of the fiber laying roll within a very short range over the limits of the suction couch roll, thereby 25 lending flexibility to the installation to meet varying conditions of stock on the wire and thus provide greater efficiency in the running of a paper making machine.

It has been found that in paper making 30 machines of approximately twenty feet, a fiber making roll, in order to be strong enough, becomes so heavy as to crush the Fourdrinier wire into the perforations of the couch roll and thereby cause rapid deterioration and wearing out of the wire.

It has also been found that, under certain 35 conditions, the increased weight of the fiber laying roll has an injurious effect on the quality of the paper web tending to create a greater amount of surface finish on one side of the sheet than on the other.

To overcome this it was necessary that the roll be constructed strong and heavy enough to withstand deflection and at the 45 same time be supported in such a way that part of its weight might be counterbalanced and the resulting pressure of the fiber laying roll on the paper regulated to whatever extent necessary.

50 According to the present invention, therefore, the essential features comprise counterbalancing mechanism for regulating the pressure of the fiber laying roll on the paper

web as described in the present specification and illustrated in the accompanying drawings forming part of the same.

Referring now to the drawings in which like characters of reference indicate corresponding parts in each figure,

Figure 1 is an end elevation showing the 60 ends of the fiber laying roll and the suction couch roll,

Figure 2 is a front elevation of the fiber laying roll and the suction couch roll,

Figure 3 is a plan of the fiber laying roll 65 and the supporting end ball bearings, partly in section,

Referring more particularly to the drawings, 10 designates the suction couch roll shell held in housings 11 at each end, while 70 12 is the fiber laying roll riding on top of the suction couch roll.

As illustrated in Figure 1, the dotted lines show the different positions of the fiber laying roll, with reference to the couch roll, 75 that can be obtained with applicant's construction. Referring now more particularly to this, the fiber laying roll 12 rotates in ball bearings 13 at each end, which in turn are supported in levers 14 to each of which is 80 attached a weighted lever arm 15 adapted to carry weights 16. The levers 14 are loosely connected through pins 17 to levers 18 in turn keyed by means of set screws 19 on the horizontal shaft 20 running parallel to and above the fiber laying roll 12. This shaft is supported at each end in bearings 21 attached to the couch roll housings 11. On one end of the shaft 20 is keyed a lever 22 by means of a set screw 23. This lever carries 85 on top a swivel screwed block or nut 24 through which passes a screw 25 provided with an operating hand wheel 26 on one end and adapted at the other end to extend into a swivel bearing block 27 supported in the bearing bracket 27a. The screw 25 is held in the swivel bearing block 27 by means of collars 28, while 29 and 30 are lock nuts for the screw 25 adapted to lock it at any desired point of its travel when operated by the 90 hand wheel 26 through the swivel screwed block or nut 24.

Set in the lever 18 is a screw 31 adapted to engage with the lever 14 as the hand wheel 26, operating the screw 25, is rotated 105 to lift the fiber laying roll clear from the

surface of the suction couch roll at any desired point within the range already referred to.

It will also be noted that the arms 15 are formed with spaced slots 15^a and that the weights 16 are provided with pins 15^b adapted to detachably engage with said slots whereby the weights are movably mounted on the arms. 32 is a cotter pin through the end of the arms 15 to prevent the weights from slipping off.

From the foregoing it will be seen that with the lever 22 locked by the nuts 29 and 30 on the screw 25, as illustrated in Figure 1, and the levers 22 and 18 keyed on the shaft 20, the fiber laying roll 12 is practically suspended from said shaft by means of the swinging pin connection 17 between the levers 18 and 14. This pin 17 then becomes a fulcrum for the lever 14 with the fiber roll 12 on one end and the weights 16 on the other end, thereby providing positive counter-balancing mechanism for regulating the pressure by a manipulation of the weights 16, on 15 of the fiber laying roll on the paper web, as may be required, thus assuring a correct and uniform finish on both sides of the sheet of paper under all conditions. The manipulation of lock nuts 29 permit locking or setting the position of the fiber laying roll at any point within a three inch range over the limits of the suction chamber of the suction couch.

Furthermore it will be seen that in order to regulate the pressure exerted by the weight of the fiber laying roll 12 on the paper web, between it and the couch roll 10, it is only necessary to adjust the weights 16 carried by the arm 15 to raise or lower the roll 12.

As many changes could be made in the above construction and many apparently widely different embodiments of our invention within the scope of the claims, constructed without departing from the spirit or scope thereof, it is intended that all matter contained in the accompanying specification and drawings shall be interpreted in an illustrative and not in a limiting sense.

What we claim as our invention is:

1. In a paper making machine, a couch roll, a fiber laying roll, counter balancing mechanism for the fiber laying roll to regulate the pressure of the fiber laying roll on the paper web, comprising a shaft supported above the fiber laying roll, levers keyed on said shaft and means operatively connected to said levers for swingingly suspending the fiber laying roll, counter balancing means carried by said supporting means and means for adjusting said shaft and retaining it in position when adjusted.

2. In a paper making machine and in combination, a couch roll, a fiber laying roll, a shaft arranged above the fiber laying roll,

levers rigidly secured to said shaft, supporting levers for the fiber laying roll, swingingly connected at one end to said levers and provided at the other end with adjustably weighted arms.

3. In a paper making machine and in combination, a fiber laying roll, counter-balancing means for said roll, comprising supporting members for the roll, weighted lever arms for said members, a shaft and means carried by said shaft adapted to swingingly engage said supporting members and means for adjusting the weights on said arms to raise or lower the fiber laying roll.

4. In a paper making machine and in combination a couch roll, a fiber laying roll swingingly suspended above the couch roll counter-balancing means for the fiber laying roll comprising weighted supporting levers, a shaft and means keyed to the shaft adapted to swingingly connect with said levers and means for adjusting the weights for said levers.

5. In a paper making machine, a fiber laying roll, supporting members for said roll, a shaft, levers, rigidly carried by the shaft swingingly connected to the supporting members, whereby the fiber laying roll is suspended and weighted arms for the supporting members and adjustably mounted weights on said arms.

6. In a paper making machine, a fiber laying roll, supporting members for said roll, a shaft, and levers, rigidly carried by the shaft, swingingly connected to the supporting members whereby the fiber laying roll is suspended and weighted arms for the supporting members and adjustably mounted weights on said arms and means for retaining the fiber laying roll in adjusted position.

7. The device as claimed in claim 6, in which the means for setting the fiber laying roll in adjusted position comprise a bracket, a lever keyed to one end of the shaft, swivel blocks carried by the lever and said bracket and a screw member provided with a hand wheel adapted to engage with said blocks and lock nuts on said screw.

8. In a paper making machine and in combination, a couch roll, a fiber laying roll, a shaft rotatably mounted in bearings above the fiber laying roll, supporting members for the fiber laying roll, swingingly connected rigid members on said shaft, adjustable counter-balancing means carried by the supporting members.

9. In a paper making machine and in combination, a fiber laying roll, counter-balanced supporting levers for said roll, a rotatably mounted shaft and connecting members rigidly carried on the shaft and swingingly connected to the supporting levers, means for adjusting the shaft and means for locking the shaft in adjusted position.

10. In a paper making machine the combination with the fiber laying roll, supported on weighted levers, of a turnable shaft having members rigidly mounted thereon and
5 adapted to be swingingly connected to the supporting levers, means for adjusting the weighted levers and means for adjusting the shaft to regulate the pressure of the fiber laying roll and means for securing the supporting levers and the shaft in adjusted position.

11. The combination with a suction couch roll of a swingably mounted fiber laying roll, means for swinging said fiber laying

roll to different positions circumferentially 15 of the couch roll and means for securing said fiber laying roll in any position to which it is moved by said last mentioned means.

12. The combination with a suction couch roll and a fiber laying roll of a counterbalancing mechanism for said fiber laying roll 20 operable to adjust both the effective pressure of the fiber laying roll and the position thereof circumferentially of the couch roll.

In witness whereof we have hereunto set 25

our hands.
CONE BARLOW.
EDWARD RICHARD CLAPP.
